UNITED STATES PATENT OFFICE.

LEVI L. LAMB, OF CHICAGO, ILLINOIS, ASSIGNOR TO THE WHITMAN & BARNES MANUFACTURING COMPANY, OF AKRON, OHIO.

DESIGN FOR AN ELEVATOR CHAIN BUCKET.

SPECIFICATION forming part of Design No. 27,625, dated September 7, 1897.

Application filed July 17, 1897. Serial No. 644,989. Term of patent 14 years.

To all whom it may concern:

Be it known that I, LEVI L. LAMB, residing at Chicago, in the county of Cook and State of Illinois, have invented and produced a new 5 and original Design for an Elevator Chain Bucket, of which the following is a specification, reference being had to the accompanying drawings, forming part thereof.

Figure 1 is an isometric perspective and 10 Fig. 2 a plan view of the bucket embodying my new design.

The leading or material feature of my design consists in the configuration produced by the two chain-links *e*, connected by the

plates *a* and *b*, forming, substantially, a right angle with each other, the plate *a* meeting the links *e* at substantially their middle and following the sides of the links in the lines *c* and *d*.

Having described my invention, what I claim as new, and desire to secure by Letters Patent, is—

The design for an elevator chain bucket as herein shown and described.

LEVI L. LAMB.
